BOBBY-PIN RECEPTACLE AND OPENER
Hazel A. Richardson, Denton, Tex.
Application April 27, 1954, Serial No. 425,808
1 Claim. (Cl. 132—1)

This invention relates to a receptacle and more particularly to a receptacle having a pin opener.

An object of the invention is to provide a new and improved receptacle having a new and improved means for opening or spreading "bobby" pins.

Another object of the invention is to provide a means for opening or spreading pins which is of simple and economical construction.

Still another object of the invention is to provide a new and improved means for opening or spreading pins which permits easy single handed manipulation and opening of the pins leaving the other hand free to perform other operations.

A further object of the invention is to provide a receptacle, having a pin opener, which is of a single piece construction and having no nooks or crevices wherein pins may become lodged.

Additional objects and advantages of the invention will be readily apparent from the reading of the following description of device constructed in accordance with the invention and reference to the accompanying drawings thereof, wherein:

Figure 1 is a perspective view of a receptacle or tray having a pin opener in accordance with the invention;

Figure 2 is a sectional view of the receptacle shown in Figure 1;

Figure 3 is a sectional view of a modified form of the receptacle;

Figure 4 is a sectional view of another modified form of the receptacle; and,

Figure 5 is a sectional view of still another modified form of the receptacle.

Referring now particularly to Figures 1 and 2 of the drawing, the pin receptacle or tray 10 includes a bottom 11 which may be provided with countersink screw holes 12 through which flat head screws may be inserted to secure the tray rigidly to the bottom of a dresser drawer, a dressing table or the like. Two side walls 13 and 14 and a rear wall 15 rise vertically from the bottom and are integral therewith. The side walls and the rear wall are thin and serve no other purpose than to define three sides of the pin receiving recess 16 of the tray.

An opener wall 17 defines the fourth side of the recess 16 and also rises upwardly from the bottom 11 of the tray. The opener wall is relatively thick or wide and has an inner surface 18 which extends upwardly and inwardly from the bottom to a common edge 19 with a downwardly and inwardly inclined upper surface 20. It will be apparent that the upper and inner surfaces 18 and 20 extend frontwardly at an acute angle from each other to form a wedge which is used to open bobby pins. Furthermore, it is preferable that the inner surface be inclined at an angle of 45 degrees or more from the bottom and that the upper surface 20 be inclined at an angle of less than 30 degrees from the horizontal, to provide the acute angle at the edge 19. The walls are preferably integral with the bottom in order that no

2

crevices or nooks may occur between the walls and the bottom in which pins could become lodged.

In use, the bobby pin tray is secured to the bottom of a drawer of a dressing table or the like by means of 5 the flat head screws 21. The tray should be fixed within comfortable reach of the user about five or six inches from the front of the drawer and near the side of the drawer which is closer to the user. For a right handed user the drawer should preferably be to the right of 10 the user. In this position the front of the open drawer does not interfere with the forearm and wrist movements of the right arm of the user and pins disposed in the tray may be pulled up without lifting the elbow sideward from the body or bending the hand and the wrist to 15 reach the pins, such movements being awkward and tiring.

The bobby pins 22 are placed in the recess 16 of the tray with the free ends 23 and 24 thereof facing the opener wall 17. When it is desired to use a bobby pin, 20 it is picked up from the tray between the thumb and the first three fingers of the right hand with the shorter or hooked end or prong 23 of the pin facing up. The forefinger is then slid toward the ends 23 and 24 of the pin to 25 guide the placement of the pin. The forearm is then rested against the front of the drawer.

The lower longer prong 24 of the pin is slipped into engagement with the inner surface 18 of the opener wall of the tray while the upper shorter prong 23 contacts the upper surface 20 of the opener wall. The hand is then pivoted upwardly at the wrist to cause the prongs 30 of the pin to slide over the surfaces 18 and 20 of the opener wall and separate from each other. The fleshy end of the forefinger then slips between the open prongs to hold the prongs in open position as the pin is lifted 35 from engagement with these surfaces to be slipped over a tress of hair held by the left hand. It will be noted that the degree to which the prongs 23 and 24 of the pin are opened is governed by the degree of pushing of the prongs against the surfaces 18 and 20 of the opener 40 wall, the maximum opening occurring when the lower longer prong touches the bottom 11 of the tray.

It will be apparent now that a receptacle or tray 10 for hair or bobby pins has been provided which includes a bottom 11 and walls 13, 14, 15 and 17 integral therewith, the opener wall 17 having an upwardly and inwardly inclined surface 18 and a downwardly and inwardly inclined upper surface 20 which converge at an acute angle to a common edge 19 to form a wedge for opening the pins. It will also be apparent that the provision of the opener wall 17 with an upper surface which is inclined downwardly toward the edge 19 provides a greater angle between the surfaces 18 and 20 and this permits the pin prongs to be separated to the maximum degree upon a relatively small movement of the prongs 23 and 24 of the pin over the wedge formed by the surfaces of the opener wall, and also causes both the prongs to spread or open simultaneously as the pin is pushed onto the wedge surfaces.

In Figure 3 is illustrated a modified form of a tray 60 25 having a bottom 26 which is not provided with holes, such as the holes 12 of the tray 10 of Figures 1 and 2 and whose opener wall 27 is of lesser thickness than the opener wall 17 of the tray 10. The tray 25 may be secured to a dresser drawer or to a glass dresser top by 65 a suitable adhesive on the under side of the bottom 26 of the tray.

Figure 4 illustrates another modified form of the tray 28 having a bottom 29, an end wall 30, side walls 31 (only one of which is shown in Figure 4) and an opener wall 32. The upper surface 33 of the opener wall is 70 inclined downwardly and outwardly to the common edge

34 with the upwardly and outwardly inclined outer surface 35 of the opener wall. It is apparent that the surfaces 33 and 35 form a wedge for opening the prongs of bobby pins in a manner similar to that described above in connection with the tray 10 of Figures 1 and 2.

Figure 5 illustrates still another form of the tray 36 which has a bottom 37 provided with apertures 38 through which screws may extend to fasten the tray to a fixed structure. Vertical side walls 39, only one of which is shown in Figure 5, and rear and front end walls 40 and 41 extend upwardly from the bottom. The tray is divided into two pin receiving compartments 42 and 43 by a partition 44 which extends transversely between the side walls 39.

The partition has two upper surfaces 45 and 46. The upper surface 45 extends downwardly and rearwardly to a common wedge edge 47 with the rearwardly and upwardly inclined side surface 48 of the partition. Similarly, the upper surface 46 extends downwardly and forwardly to a common wedge edge 49 with the frontwardly and forwardly inclined side surface 50 of the partition.

It will be apparent that the surfaces 45 and 48 and the surfaces 46 and 50 form wedges for opening the prongs of bobby pins in a manner similar to that described in connection with the tray 10 of Figures 1 and 2.

It will now be seen that the various forms of the tray may be made of plastic, glass or other substance and that they are preferably made in a single integral piece in order to avoid any crevices or nooks between the walls and bottoms of the trays in which pins may lodge. It will also be apparent that the upper surfaces of the wedges provide an area on which ornamental or ad-

vertising matter may be painted, inscribed or otherwise secured.

The foregoing description of the invention is explanatory only, and changes in the details of the construction illustrated may be made by those skilled in the art, within the scope of the appended claim, without departing from the spirit of the invention.

What I claim and desire to secure by Letter Patent is:

A device of the type described including: a tray having 10 a bottom, three vertical walls extending upwardly from the bottom, and a fourth wall having an upwardly and inwardly inclined inner side surface and an upwardly and outwardly inclined upper surface, said surfaces of said fourth wall having a common edge and forming a 15 wedge extending laterally inwardly over and spaced above the bottom of said tray, said inner side surface extending at an acute angle to the upper surface from said common edge and at an acute angle and spaced above the bottom of said tray.
